UNITED STATES PATENT OFFICE.

JOSHUA MASON, OF PATERSON, NEW JERSEY.

RADIATOR.

SPECIFICATION forming part of Letters Patent No. 258,092, dated May 16, 1882.

Application filed February 20, 1882. (No model.)

To all whom it may concern:

Be it known that I, JOSHUA MASON, of Paterson, in the county of Passaic and State of New Jersey, have invented certain new and 5 useful Improvements in Radiators, of which the following is a specification.

My invention more especially relates to radiators employed for heating by hot water; and its principal object is to so construct such 10 a radiator as to provide for the circulation of a small quantity of water in contact with a radiating-surface of comparatively great area, whereby a very rapid circulation is produced.

To this end my invention consists in the 15 combination, in a radiator, of an upper and a lower water or steam chamber or head, outer and inner tubes, between which are annular water or steam spaces, the said outer tubes connecting the two chambers or heads, and 20 the said inner tubes passing through the former and through both chambers or heads, and a central tube communicating with the upper chamber or head, and having a water or steam inlet at its lower end, thus affording provision 25 for a rapid circulation of water up through the central tube and down through the spaces between the outer and inner tubes while the air circulates around the outer tubes and through the inner tubes. The lower chamber or head 30 may be constructed with a passage or conduit separate from the remaining portion thereof, and the lower end of the said central tube may communicate with said passage or conduit.

In the accompanying drawings, Figure 1 35 represents a vertical section of a radiator embodying my invention, taken through the inner and outer tubes. Fig. 2 is a sectional view of the two heads or chambers and the central tube, but a side view of the outer tubes. Fig. 40 3 is a transverse section upon the dotted line $x x$, Fig. 1; and Fig. 4 is a transverse section upon the dotted line $y y$, Fig. 2.

Similar letters of reference designate corresponding parts in all the figures.

45 A B designate respectively the lower and upper heads of the radiator, both hollow, and the lower one of which is preferably provided with a water passage or conduit, a , made integral with it, but separated from the main 50 portion of the chamber or head for a purpose to be hereinafter described.

C D designate respectively outer and inner tubes arranged concentrically, the latter within the former, as shown clearly in Figs. 1 and 4. The outer tubes, C, are connected to the upper side of the lower head and the under side of the upper head in any suitable manner—as, for instance, by making holes in the heads to exactly fit the tubes and then driving the latter in. The inner tubes, D, pass entirely 55 through the outer tubes, and also through the two chambers or heads, they being secured in the under side of the lower chamber or head and in the upper side of the upper chamber or head, as clearly shown in Fig. 1. The said inner tubes may be secured in the lower chamber or head by screwing or driving them in, so as to make a tight joint, and they are preferably secured at their upper ends by means of nuts E, of a form for which were granted to 60 me Letters Patent No. 153,776, dated August 4, 1874. The tubes D are secured in these nuts by driving or screwing, and the latter are screw-threaded externally, and engage with screw-threaded holes or sockets in the upper side of 65 the upper chamber or head, B. I prefer to use nuts of this kind, for the reason that they comprise corrugated portions of thin metal, and compensate readily for any difference in the longitudinal expansion of the outer and inner 70 tubes, thus preventing leakage and the straining of the parts of the radiator, which otherwise might ensue.

F designates a central tube or pipe, secured at its upper end in the under side of the chamber or head B, and in communication at the lower end with the passage or conduit a in the lower chamber or head, A, or with another inlet which receives the heated water through a pipe, b , from a boiler.

G designates the pipe through which water is delivered from the radiator after passing through the same, and a small pipe, c , may be connected with this pipe to supply the water which escapes from the system of radiators 95 and heating-pipes by leakage, evaporation, or otherwise.

The pipe c may communicate with a street-main or with a tank placed high above the radiator, and by it the full supply of water for 100 circulation is maintained.

In the ordinary operation of the radiator,

when it is placed above the boiler, as it usually will be, the heated water enters from the boiler through the pipe *b*, and thence passes through the conduit or passage *a*, through the 5 central tube, *F*, to the upper chamber or head *B*, and thence down the spaces between the outer and inner tubes, *C D*, to the lower chamber or head, *A*, and out through the pipe *G* to the boiler of another radiator, or back to the 10 boiler.

By the term "central" as applied to the tube *F*, I do not mean that it is exactly central within the radiator, but only that it is arranged within the circle or other figure formed by the 15 outer pipes, *C*. In place of one tube *F*, two or more might be used.

It will be observed that the water ascending in a solid column through the center tube, *F*, is cooled very little and much less rapidly than 20 when descending through the small annular water-spaces between the tubes *C* and *D*, and that therefore a rapid circulation is easily kept up, owing to the rapid natural circulation of water down the water-spaces between the 25 tubes *C D*. The outer surface of the tubes *C* and *F*, the inner surface of the tubes *D*, and the outer surface of the chambers or heads all combined present a very large heating-surface for heating air, rendering this a very effective 30 radiator.

In certain cases it might be necessary to have the radiator below the boiler from which

it derives its hot water, and in such cases water may enter the radiator through a pipe in the upper head or chamber and pass down between the outer and inner tubes, *C D*, and thence outward through the pipe *G*, the pipe *b* being in such case disconnected and the hole 35 plugged up.

It will be seen that by my invention I provide a radiator in which the circulation is very 40 rapid, which is a result greatly to be desired in heating by hot water.

What I claim as my invention, and desire to secure by Letters Patent, is—

1. The combination, in a radiator, of an upper and a lower water or steam chamber or head, outer and inner upright tubes, the former of which connect the two water chambers or heads, and the latter of which pass through 50 the former and through both chambers or heads, and a central tube communicating with the upper chamber or head, and having an inlet at the lower end thereof, substantially as and for the purpose specified. 55

2. The combination of the lower head or chamber, *A*, constructed with the passage or conduit *a*, the upper head or chamber, *B*, the outer and inner tubes, *C D*, and the central tube, *F*, substantially as specified.

JOSHUA MASON.
